UNITED STATES PATENT OFFICE.

GEORGE RYAN, OF BRANTFORD, ONTARIO, CANADA.

FEED-REGULATOR FOR MACHINES FOR SPINNING HEMP, &c.

SPECIFICATION forming part of Letters Patent No. 398,848, dated March 5, 1889.

Application filed July 7, 1888. Serial No. 279,295. (No model.)

To all whom it may concern:

Be it known that I, GEORGE RYAN, machinist, of the city of Brantford, in the county of Brant, in the Province of Ontario, Canada, 5 have invented a certain new and Improved Feed-Regulator for Machines for Spinning Hemp, &c., of which the following is a specification.

The invention relates to a new and useful 10 feed-regulator for machines for spinning manila and sisal hemp and other fibers, especially for binding-twine and rope-yarns.

The object of the invention is to arrange a 15 simple device by which the sliver feed-rollers shall be instantly and automatically stopped the moment that any over thickness in the sliver reaches the nipper; and it consists in the peculiar combinations and the construction and arrangement of parts, all as more 20 fully hereinafter described and claimed.

Figure 1 is a perspective view showing the portion of the spinner connected with my invention. Fig. 2 is an enlarged detail of the nipper, partly in section. Fig. 3 is an enlarged 25 view, also partially in section, of the driving-gear for feed-rollers.

A is the driving-pulley, which is constantly in motion while the machine is in operation. This pulley is connected by a belt, B, to the 30 pulley C, secured to the spindle D.

E is a pulley loosely journaled on the spindle D. This pulley E has a pawl, F, pivoted on it, as indicated, and designed to engage with a ratchet-wheel, G, which is rigidly fastened to the pulley C or spindle D.

H is a lever pivoted on the pulley E, through which a hole is made to permit the passage of one end of the lever H, so that it may project below the pawl F, as indicated in Fig. 3. The 40 other end of this lever H extends toward an inwardly-beveled flange, a, formed on the wheel I, so that when the said wheel is moved toward the pulley E the beveled flange a will come in contact with the lever H, causing it 45 to tilt on its pivot and lift the pawl F, as indicated in Fig. 3. A bell-crank lever, J, is pivoted at b, as shown, and one end of it is forked to engage with the wheel I. Its other end has a pin, d, projecting from it and fitting 50 into an elongated hole made in the end of the lever K. This lever is pivoted at e, as shown,

and its other end connects with the base of the nipper L. This nipper is supported on the upper end of the bar M, the lower end of which is connected to a journaled rod, N, so 55 that the bar M, carrying the nipper L, may rock laterally. Stops O, adjustably connected to the spindle P by set-screw o, regulate the rocking distance of the bar M.

Q is a belt connecting the pulley E with the 60 pulley R, which is fastened to the spindle of the sliver feed-roller S.

The tension of the nipper L is regulated in the usual manner to permit the proper-sized sliver to pass through it. When a thick portion of the sliver reaches the nipper, it will not pass freely through the nipper. Consequently the nipper, which is held in position by the spring T, of suitable tension, will be caused to instantly rock on its pivot, and, being connected by the levers K and J to the wheel I, the said wheel is moved toward the pulley E, causing the beveled flange a on the clutch I to come in contact with and press down the lever H, forcing the opposite end of 75 the said lever H upwardly and raising the pawl F out of contact with the ratchet-wheel G, as indicated in Fig. 3. Consequently the pulley E is instantly disconnected from the spindle D, which disconnection of course stops 80 the motion of the pulley E, and through it the sliver feed-roller S.

What I claim as my invention is—

1. A nipper, L, a pivoted bar, M, carrying said nipper, and a spring, T, for holding the 85 same in position, in combination with the pivoted lever K, having one end connected to the nipper, a bell-crank, J, connected to the opposite end of the lever K, the revolving shaft D, the inwardly-beveled flanged wheel I, movably mounted on said shaft and connected with the bell-crank, a pulley, E, a lever, H, and a pawl, F, carried by said pulley E, and a ratchet-wheel carried by said shaft D, and a pulley, as C, also mounted on said shaft, for 90 receiving the motive power, substantially as described.

2. A nipper, L, a pivoted bar, M, carrying said nipper, and a spring, T, for holding the same in position, and the adjustable stops O, 100 in combination with the pivoted lever K, having one end connected directly to the nipper,

a bell-crank, J, connected to the opposite end of the lever K, the revolving shaft D, the inwardly - beveled flanged wheel I, movably mounted on said shaft and connected with the 5 bell - crank, a pulley, E, mounted on shaft D, a lever, H, and pawl F, carried by the pulley E, a ratchet-wheel mounted on said shaft and engaged by the pawl, and a pulley, also

mounted on said shaft, for receiving the motive power, substantially as described.

Brantford, June 12, 1888.

GEORGE RYAN.

In presence of—

FRED CHALCRAFT,
W. H. MOORE.
